AMPLIFICATION SYSTEM

Application filed May 1, 1928. Serial No. 274,174.

- The invention relates to an amplifying system for weak electric currents and more especially to a system utilizing thermionic valves or so-called "audion" tubes for this purpose.
- 5 In the amplification of these currents as heretofore conducted provision has been made to render the amplification as distortionless as possible, more especially through the prevention of any appreciable flow of current in the
- 10 grid circuit, thus also insuring a minimum requirement of energy from the applied signal or other energizing source to be amplified.
- This substantially distortionless amplification has been accomplished by impressing on
- 15 the grid of an amplifying valve a potential permanently more negative than that of its cathode, or "biasing" negatively said grid. The magnitude of this bias or negative potential depends on the grid potential-plate current characteristic of the particular tube employed, it being understood that the amount of grid current will be negligible until the signal voltage attains a value sufficient to make the grid reach or exceed the filament potential.
- 20 Actually, appreciable grid current flows at a slightly negative potential, the current then flowing introducing a shunt load on the signal source and, in the ordinary well-known amplification circuit causing distortion of the
- 25 input signal wave form which is correspondingly magnified in the amplified circuit. If the valve, however, were operated without providing the aforesaid grid bias, the entire
- 30 positive pulsations of the signal would be subject to this shunt load and the negative pulsations be subjected to practically no load, the distortion, therefore, being especially severe.
- 35 Vacuum tube design has, therefore, been along the lines of constructing tubes such that their characteristic curve will show as great a useful portion to the negative side of the zero grid potential line as possible in order to give maximum undistorted output. As a
- 40 matter of fact, some tubes in use have no useful portion on the positive side. This, however, entails a loss of amplifying power of the tube, that is to say, in the number of milliamperes change of the plate current for a unit
- 45 change in the grid voltage and therefore less
- 55 steep gradient. If it were possible to operate the tubes without this distortion, using tubes whose characteristic curve shows a much steeper gradient, with useful portions substantially equal on both sides of the zero grid potential line, a very much smaller signal voltage would have to be applied to equal the output of the biased tube, or a much greater amplification ratio would be attainable.
- 60 The present invention has for its object a novel system whereby this increased amplification ratio is secured, it being possible to operate a tube under substantially distortionless amplification and with the tube having no bias whatsoever or potential impressed permanently on its grid; or, if any be thus permanently impressed thereon, the same being a positive one. I accomplish this by a novel
- 65 system or method of balancing which includes setting up positive grid currents in phase with the oscillating voltage applied to the input circuit of the tube and thereby rendering their effect on distortion negligible. This entails no sacrifice of amplification ratio, although the grid circuits consume appreciable energy in their operation yet this is more than compensated for by the increased amplifying power. By properly designing the circuits
- 70 to allow for the grid energy consumption, excellent quality is attained and at tremendous
- 75 volumes.
- 80 A further object of the invention contemplates a system wherein grid leaks may be dispensed with, provision being made for the discharge of any accumulated potential through circuits employed in the operation of the novel system.
- 85 In carrying out this system, use is made of suitable compensating means included in the grid circuit whereby the grid currents resulting from the application of positive and negative potentials are substantially equal though opposite in direction. For example, two thermionic valves or vacuum tubes may be so interconnected with each other and with the input circuits that the positive grid current flowing therein is balanced or compensated so that distortion is substantially obviated and a high amplification ratio attained.
- 90
- 95
- 100

As a practical arrangement for carrying out this compensation, the modulating grid element of the one tube is placed in direct electrical communication with the cathode of the other tube, while the grid of the latter is similarly in direct electrical communication with the cathode of the first-named tube and both the said grid and cathode of the last-named tube being in direct electrical communication with the input circuit, whereby the combined grid circuits function like an equivalent ohmic resistance placed across the input circuit—alternating positive and negative portions of the applied signal current of the input circuit equally and in accordance with the applied voltages.

The nature of the invention, however, will best be understood when described in connection with the accompanying drawings, in which:

Fig. 1 is a diagrammatic view illustrating the novel amplification system as applied in connection with a microphone.

Fig. 2 illustrates one arrangement for combining the outputs of the two thermionic valves of the system illustrated in Fig. 1.

Fig. 3 is a diagrammatic representation of the novel amplifying system embodying a modification.

Fig. 4 is a diagrammatic view of the novel amplifying system connected with, for example, a detector tube or lower amplification stage.

Figs. 5 and 6 are similar views illustrating different means of coupling.

Figs. 7 and 8 are diagrammatic views of the amplifying system showing a modification in the compensating arrangement.

Fig. 9 illustrates the arrangement for feeding the filaments of the tubes employed in the novel amplifying system from a source of alternating current.

Referring to Fig. 1 of the drawings, an input circuit is indicated, 10 designating a suitable inductance thereof receiving a single voltage in any well-known or special manner and from which inductance extends a lead 11 connected directly to the grid 12 of an amplifying tube 13, preferably of so-called "hard" or highly evacuated type and of high amplification constant, and embodying also the plate or anode 14 and the filament or cathode 15. A further lead 16 directly connects the latter to said inductance; and the filament or cathode 15 and plate or anode 14 are connected in the usual manner to the "A" and "B" batteries 17 and 18 respectively in accordance with the standard practice. The arrangement hereinbefore described differs in no essential respect from the ordinary amplifying circuit except that no "C" battery is included in circuit for biasing negatively the grid 12, nor is there provided any grid-leak in connection therewith. The novel system operates best when preceded by a signal

source of low impedance, for example, a carbon microphone 19 which feeds the input circuit, through the inductance 10 matched thereto, excellently because of its ability to deliver current even at fairly high stepped-up voltage.

In accordance with the invention, however, there is associated with the tube 13 a similar tube 20 embodying the grid 21, anode 22 and cathode 23; and the grid 12 of the former tube is directly connected with the cathode 23 of the latter tube by means of a lead 24, while its grid 21 in turn is directly connected to the cathode 15 of the tube 13 by means of a lead 25. Moreover, it will be noted that both the grid 21 and its cathode 23 are thereby also directly connected to the input circuit. Means, independent of the filament and plate energizing batteries 17 and 18, are also to be provided for the cathode 23 and anode 22 of this second tube, for example "A" and "B" batteries 26 and 27 respectively.

It will be noted that, if the amplifying arrangement hereinbefore described, two separate and independent output circuits result, one coming from each of the tubes 13 and 20, Fig. 1, so that separate apparatus may be operated thereby, for example, two loud speakers or the like (not shown). However, the two circuits may be electrically combined in proper phase, if desired, for example by means of oppositely wound primaries 14' and 22' respectively associated with a common secondary, as indicated in Fig. 2.

When it is desired to bias the grid 12 of the one tube 13, this may readily be effected by including in series in the lead 11 a "C" battery 28 or like expedient, Fig. 3, for impressing permanently on the said grid the desired potential which, it will be understood, will always be more positive than the potential of the corresponding cathode 15 of said tube. This provision of a positive bias is more especially valuable in the leading stages of amplification, rather than in the final or power stages.

In the event of the input circuit having a condenser 29, Fig. 3, in series in the lead 11 the grid current of each tube under static conditions may be considered as returning to its filament through the grid filament path of the other tube. The oscillating grid currents set up, however, may pass through the capacity and the applied circuit.

When the novel amplifier circuit is to be coupled to a vacuum tube, as the tube 30, Fig. 4, this tube should be of fairly low impedance and the coupling may be effected in any of the customary ways. For example, as indicated in Fig. 4, an impedance 31 may be bridged across the plate circuit of said tube to carry off the direct current, while a condenser 32 is inserted in series in the lead 33 therefrom to allow the alternating voltages impressed on the grid circuit of the tube to

be continued to the amplifying portion comprising the two tubes 34 and 35 interconnected as hereinbefore described.

In Fig. 5 a resistance coupling is indicated, the resistance element 36 being bridged across the plate circuit of the tube 37; while in Fig. 6, a typical transformer coupling is shown, the primary of transformer 38 being bridged across the plate circuit of tube 39 and matched to its plate impedance, while the secondary thereof is matched to the grid impedance of the grid circuit to attain maximum efficiency. The matching is designed for the desired frequency, say approximately 800 cycles.

It will be observed that no grid leaks are included in the foregoing embodiments as the same are not required, for a grid circuit of one tube is free to discharge through the grid circuit of the other tube of said pair of amplifying tubes.

Reference being had to Fig. 7, this balancing or compensation may be accomplished, also, by disconnecting entirely the plate circuit of one of the tubes as the tube 40, or utilizing a "plateless" tube, and including a variable resistance element 41 in the grid lead 42 from the grid of the other tube 43. This resistance is to be adjusted to give equal grid-current grid-voltage curve with the main amplifier tube 43, as the usual two-element tube does not possess generally the desired characteristic for matching the grid-current grid-voltage of said tube 43. Or a two-element tube or its equivalent such as a crystal 35 or other uni-lateral device (not shown) whose voltage-current curve can be adjusted to equal more or less exactly the voltage-current curve of the amplifier tube may be utilized for this purpose.

Means may be devised to reduce the grid current, for example, by placing in series the grid circuits of two or more tubes 46 and 47 combined with a tube 48, Fig. 8, and compensating as hereinbefore noted, as with the variable resistance element 49 and "plateless" tube 48.

Moreover, the filaments or cathodes are adapted for energization from a source of alternating current, for example, for the tubes 50 and 51, Fig. 9, their cathodes may be fed from a source 52 of alternating current through a suitable transformer 53; and the return lead 54 of the one grid 55 is not required to be made to return to the electrical center 55 of the other tube for minimized hum, thus eliminating the necessity for center taps in the transformer winding. This results from the return to the proper side of the windings (taking into account phase relation) of the one grid which receives a positive pulsation while the other neutralizes it with a negative pulsation. Furthermore, the low impedance grid circuits make said circuits less susceptible to picking up hum.

It will be understood that the resistance of

the novel grid circuits hereinbefore described is much lower than is the case with negatively biased amplifier circuits; and some loss is therefore involved, but by careful selection of the filament and plate voltages this loss can be minimized.

The general operation of the improved amplifier system is as follows:

Referring to Fig. 1, it is obvious that the grid current of each tube 13 and 20 returns through the input to its filament without bias; and in the event of said input circuit having a condenser in series, as indicated in Fig. 3, the grid current of each tube may be considered as returning to its filament through the grid filament path of its other and associated tube. As a signal is applied, in the input circuit represented by the lead 11-16, the grid 12, for example, being positive with respect to lead 16, an electron current flows in the tube 13 from its filament or cathode 15 to the said grid 12 through the lead 11 of the input circuit and lead 16 thereof back to said filament. At this instant, the grid 21 of tube 20 is negative with respect to its filament 23 and no current can flow from this filament to the grid 21. Conversely, when lead 16 and the connected grid 21 are positive with respect to the grid 12 and connected lead 11 of the input circuit, current flows from the filament 23 to its grid but no current can flow in the tube 13 between its filament 15 and grid 12, which are both negative at this instant.

An oscillating voltage applied to the input circuit will, therefore, set up oscillating currents in the interconnected grid filament circuit of the two tubes and in phase with the applied oscillating voltage. The said interconnected circuit will then act as an ordinary ohmic resistance across the input circuit 11-16, alternating positive and negative portions of the applied signal equally since the tubes 13 and 20 are designed to match.

As the curve of grid-current against grid-voltage is, in actual operation of the circuit, substantially a straight line within the working limits, equal increases of voltage will result substantially in equal increases of the grid current so that reverse currents will result from reverse voltages and in equal amounts for equal variations thereof.

Moreover, in the use of an amplifying system employing one or more stages of amplification, the preceding stages in a system of the nature herein set forth may be operated at positive or zero potential; and it has been found generally advantageous to operate one or more leading stages at a predetermined positive bias. Since the variable grid impedance is the factor which usually produces distortion in amplifying systems, there is selected in the present embodiment a point in the grid-voltage grid-current curve at which this grid impedance, although low, is constant. The said curve is substantially a

straight line over a definite positive portion; and the biasing point selected is to be located substantially midway between the zero voltage position and the point where said curve begins to depart from its straight line characteristic. This will permit a tube to handle without distortion fairly large variations in voltage; but when the compensated arrangement is to be provided as in larger 10 amplifications, as the final or power stages of a system, the grid is to be operated at substantially the zero voltage position—the combined grid impedances of the two tubes employed being equal only to that of one tube. 15 In connection with the operation at a point along the curve, namely a predetermined positive bias, it will be appreciated that both a positive and negative variation of the signal beyond the bias portion will be affected substantially alike so that no serious distortion effects will result. With this system of operation, therefore, a steady flow of current prevails in the grid circuit under static conditions, which current increases and decreases 20 in value with the input signal; and the positive bias therein makes for lower operating plate impedance of the tube. 25

When positively biased, a lower operating plate impedance of the tube results, making 30 the same ideal for preceding a compensated stage of amplification.

Moreover, when a coupling transformer is employed between stages, the flow of direct current in the plate winding thereof tends 35 to saturate the transformer core; but when connected with a positively biased tube of the character hereinbefore described, the direct current flowing through the grid may be applied in such a direction as to counteract 40 the effect of the aforesaid plate current of the tube of a preceding stage of amplification and thus prevent saturation and obviate the necessity for a bulky transformer core.

I claim:

45 1. In an amplifying system having a thermionic valve with controlling element, and anode and cathode included in a suitably energized circuit, and an input circuit connected to the said controlling element and cathode: a unilateral device included in the said input circuit, having its voltage-current characteristic adjusted to match the grid-voltage grid-current characteristic of said thermionic valve and thereby to direct current through 50 said unilateral device such that equal positive and negative voltages applied to the input circuit cause substantially equal flows of current respectively between said cathode and the said controlling element and through the 55 said unilateral device.

60 2. In an amplifying system having a thermionic valve with controlling element, and anode and cathode included in a suitably energized circuit, and an input circuit connected to the said controlling element and cath-

ode: a unilateral device included in parallel with said input circuit, having its voltage-current characteristic adjusted to match the grid-voltage grid-current characteristic of said thermionic valve and thereby to direct 70 current through said unilateral device such that equal positive and negative voltages applied to the input circuit cause substantially equal flows of current respectively between said cathode and the said controlling element and through the said unilateral device. 75

3. In an amplifying system having a thermionic valve with controlling element, and anode and cathode included in a suitably energized circuit, and an input circuit connected to the said controlling element and cathode: a second thermionic valve with controlling element, and anode and cathode included in a suitably energized circuit, the controlling element thereof being connected to the said input circuit to direct current between the last-named cathode and last-named controlling element such that equal positive and negative voltages applied to the input circuit will cause substantially equal flows of current 80 respectively between the first-named cathode and its controlling element and the last-named cathode and its controlling element. 85

4. In an amplifying system having a thermionic valve with controlling element, and anode and cathode included in a suitably energized circuit, and an input circuit connected to the said controlling element and cathode: means for impressing upon the controlling element of said valve a potential 95 more positive than that of its cathode; and a unilateral device included in the said input circuit, having its voltage-current characteristic adjusted to match the grid-voltage grid-current characteristic of said thermionic 100 valve and thereby to direct current through said unilateral device such that equal positive and negative voltages applied to the input circuit cause substantially equal flows of current respectively between said cathode and the said controlling element and through the 105 said unilateral device.

5. In an amplifying system having a thermionic valve with controlling element, and anode and cathode included in a suitably energized circuit, and an input circuit connected to the said controlling element and cathode: a second thermionic valve with controlling element, and anode and cathode included in a suitably energized circuit, the controlling element thereof being connected to the said input circuit and to the first-named cathode and the cathode thereof to the first-named controlling element to direct current between the last-named cathode and last-named controlling element such that equal positive and negative voltages applied to the input circuit will cause substantially equal flows of current respectively between the first-named cathode and its controlling element and the 115 120 125 130

last-named cathode and its controlling element.

6. In an amplifying system having a thermionic valve with controlling element, and anode and cathode included in a suitably energized circuit, and an input circuit; a second thermionic valve with controlling element, and anode and cathode included in a suitably energized circuit, the grid-current grid-voltage characteristic of the second valve being matched to the grid-current grid-voltage characteristic of the first-named valve and the controlling element of each valve being connected to the cathode of the other and the said controlling elements and cathodes to the input circuit.

7. In an amplifying system having a thermionic valve with controlling element, and anode and cathode included in a suitably energized circuit, and an input circuit; means for impressing upon the controlling element of said valve a potential more positive than that of its cathode; and a second thermionic valve with controlling element, and anode and cathode included in a suitably energized circuit, the grid-current grid-voltage characteristic of the second valve being matched to the grid-current grid-voltage characteristic of the first-named valve and the controlling element of each valve being connected to the cathode of the other and the said controlling elements and cathodes to the input circuit.
